UNITED STATES PATENT OFFICE.

WILLIAM P. COLDREN, OF LEBANON, PENNSYLVANIA.

APPARATUS FOR MAKING SEALING-RINGS FOR CANNING-JARS.

SPECIFICATION forming part of Letters Patent No. 747,377, dated December 22, 1903.

Application filed July 30, 1903. Serial No. 187,654. (No model.)

To all whom it may concern:

Be it known that I, WILLIAM P. COLDREN, a citizen of the United States, residing at Lebanon, in the county of Lebanon and State 5 of Pennsylvania, have invented certain new and useful Improvements in Apparatus for Making Sealing-Rings for Canning-Jars; and I do declare the following to be a full, clear, and exact description of the invention, such 10 as will enable others skilled in the art to which it appertains to make and use the same.

My invention is an improved apparatus for making lipped sealing-rings used for sealing canning-jars and the like; and it consists in 15 the construction and combination of devices hereinafter described.

My invention further relates to improvements in the construction of lipped sealing-rings.

20 In the accompanying drawings, Figure 1 is a longitudinal sectional view of my improved apparatus for making lipped sealing-rings. Fig. 2 is a transverse sectional view of the same, taken on the plane indicated by the line *a a* of Fig. 1. Fig. 3 is a similar view taken on the plane indicated by the line *b b* of Fig. 1. Fig. 4 is a similar view taken on the plane indicated by the line *c c* of Fig. 1. Fig. 5 is a detail elevation of the rubber tube 25 from which the sealing-rings are cut at an initial stage of the manufacture of said tube. Fig. 6 is a similar view showing the form of the tube at a subsequent stage of the manufacture thereof. Fig. 7 is a similar view 30 showing the form of said tube at a following stage of the construction thereof before the tube is discharged from the apparatus.

In the embodiment of my invention here 35 shown I provide a vessel 1 of suitable size and shape and made of suitable material, which is adapted to hold a quantity of rubber or gum composition in a molten fluid condition and is provided on its upper side at one end with a hopper 2, through which the 40 melted rubber is supplied thereto. At the opposite end of the vessel is a former spout or tube 3, which is internally cylindrical and is provided, preferably on its upper side, with an interiorly-disposed longitudinal groove 4, 45 the inner end of which terminates at some distance from the inner end of said former-tube, as at 5. This groove 4, which is a former-

passage, is here shown as of substantially semicylindrical shape to correspond with the shape of the lips formed on the outer sides 55 of the sealing-rings. The shape of this groove or passage may be varied without departing from the spirit of my invention. The inner end of the former spout or tube 3 is here shown as screwed in an annular groove 6 in 60 the outer side of a collar 7, which collar is secured on the discharge end of the vessel 1 and is provided with a central opening 8, in which is centered and supported the inner end of the cylindrical former-mandrel 9, which 65 is concentric with the bore of the former-tube. The inner end of the said former-mandrel is preferably tapered, as at 10, and the same is also formed with a reentrant beveled surface 11, forming an inclined plane 70 which converges outwardly toward the inner side of the former-tube and opposite that portion of the former-tube between the inner end of the groove or passage 4 and the inner end of the former-tube. An opener 12, which is 75 here shown as a blade tangential with relation to a circle concentric with the mandrel and former-tube, is disposed between the mandrel and former-tube at their inner ends and is preferably opposite the reentrant surface 11 of the mandrel and former passage or groove 4 of the former-tube, but may be otherwise disposed, if desired.

Within the scope of my invention any suitable means may be employed for forcing the 85 melted rubber or gum composition from the vessel 1 through the former-spout, in which the mandrel is disposed and centered, and it will be understood that the rubber, as it hardens during its passage through the former 90 spout or tube and around the mandrel, will form a cylindrical tube, and that by cutting said tube cross-sectionally sealing-rings of 95 suitable thickness may be formed. In the form of my invention here shown a screw 13, which acts as a plunger, is disposed in the vessel 1 and provided with a crank 14, whereby it may be turned to force the molten rubber or gum composition from the vessel 100 through the bore of the former-tube and around the mandrel. Owing to the beveled reentrant surface 11 at the inner end of the mandrel opposite the space in the former-tube between the inner end thereof and the inner

end of the groove or passage 4, the tube of rubber or gum composition formed by the passage of the material through the former-tube will be provided at the point at and contiguous to the plane indicated by the line *aa* of Fig. 1 with a reëntrant portion *d*, as shown in Fig. 5. The compression exerted by the reëntrant surface 11 of the mandrel 9 on the inner side of the rubber or gum tube as it passes outwardly on the mandrel and within the former-tube will force the reëntrant portion *d* of the rubber or gum composition tube outwardly and compress the said rubber or gum composition tube while it is still plastic into the former groove or passage 4, so that the bead *e* will be formed exteriorly of the rubber or gum composition tube and the inner side thereof will be of true cylindrical form. The opener 12 initially opens one side of the rubber or gum composition tube, as at *f*. Said opener terminates at a point substantially opposite the inner end of the former groove or passage 4, so that during a later stage in the formation of the rubber or gum composition tube the sides of the opening *f* therein, which sides overlap, reunite, so that the tube becomes entire before it is discharged from the machine.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus fully described my invention, what I claim as new, and desire to secure by Letters Patent, is—

1. In apparatus for making lipped sealing-rings, the combination of a former-tube having an internal longitudinal groove terminating short of the inner end thereof, and a mandrel in said tube having a reëntrant surface converging outwardly toward the inner side of said former-tube and opposite that portion thereof between its inner end and the inner end of the said groove. 50

2. In apparatus for making lipped sealing-rings, the combination of a former tube, a mandrel therein, and means to force molten rubber or gum composition between them and thereby form a tube of such material, 55 means to open one side of said tube longitudinally, said means being spaced from the discharge end of the former-tube, so that the sides of the opening formed in the rubber or gum composition tube reunited during the passage thereof through the former-tube.

3. An apparatus for forming a tube of rubber, gum composition or the like for use in the manufacture of lipped sealing-rings, having means to initially form a reëntrant portion in the bore of said tube, and means to subsequently press said reëntrant portion outwardly and form a longitudinal bead on the outer side of said tube. 65

In testimony whereof I have hereunto set my hand in presence of two subscribing witnesses.

W. P. COLDREN.
